WINDOW SASH BALANCE

Harry B. Foresman, Oklahoma City, Okla.

Application August 23, 1948, Serial No. 45,716

4 Claims. (Cl. 292—76)

1

The present invention relates to mechanism for adjustably positioning vertically slidable window sash, and more particularly to spring mechanism for retaining such sash in various positions of vertical adjustment.

The principal object of the present invention, is to provide a spring mechanism which will eliminate, or supplant, the conventional sash-cords, pulleys, and sash-weights.

An important object of the present invention is to provide a spring tension unit which, when installed, resides on the inside surface of the side member of a window frame, thus making it possible to eliminate the conventional sash weight wells or channels usually built into the exteriors of said side members.

Another object is to provide a mechanism of this class which is simple to install, has few moving parts to become worn or to get out of order, and which is cheap to manufacture.

A further object is to provide a spring friction device capable of being compounded to accommodate heavy weight sash.

An additional object is to provide a friction producing loop-type spring, adapted to reside in a vertical channel in the outside edge surface of a vertically sliding window sash, said spring capable of being installed upon or removed from the sash without dismounting the sash from the window frame, and without removing any of the frame's stop-strips.

Another object is to provide such spring with resilient reinforcing elements which may be inserted within the spring loop in order to increase its friction producing capabilities.

A further object is to provide a spring of this class, which can be used as an anchor for one end of a helical sash lifting spring.

Other objects will be apparent from the following description, when taken in conjunction with the accompanying two sheets of drawings, wherein:

Figure 1 is an elevational view of a conventional window frame, housing two vertically slidable window sashes, and showing in dotted lines, two of the devices of the present invention operatively installed;

Figure 2 is an enlarged vertical sectional view through one side of the frame and one of the sashes, and illustrating the device of the present invention as it appears when the sash is in its lowermost position;

Figure 3 is a similar view illustrating the device as it appears when the sash is raised;

Figure 4 is an enlarged perspective view of one of the friction spring members, and also showing a reinforcing spring which is adapted to be removably inserted within the first spring member;

2

Figure 5 is a view somewhat similar to Fig. 3, but illustrating one of the friction springs installed without any lifting spring; and,

Figure 6 is a fragmentary vertical sectional view through the side window frame member and the lower portion of a sash, the view illustrating installation of two of the friction springs and one of the reinforcing springs.

Like characters of reference designate like parts in those figures of the drawings in which they occur.

In the drawings:

The reference numeral 1 indicates, as a whole, a conventional window frame having an upper sash 2 and a lower sash 3 slidably mounted between its two vertical side members. The two sashes may be of any conventional type which includes a pair of vertical side rails 4, a horizontal top rail 5, and a horizontal bottom rail 6.

20 The window frame 1 may be of any conventional type, including a horizontal sill 7, a horizontal top plate 8, and two parallel vertical side members extending between the sill and the plate. The left hand one of these two vertical side members is shown in Figs. 2, 3, 5 and 6, and is indicated by the reference numeral 9.

Any suitable mechanism may be provided for balancing the weight of the sashes 2 and 3, for instance, the conventional sash weight, sash cord, and pulley could be used, or as shown in Figs. 2 and 3, a helical retrieving spring 10 may be used for this purpose.

The device of the present invention is for the purpose of providing frictional tension between the outer edge surface of the side rail 4 of the sash, and the inner surface of the side member 9, so as to retain the sash in any vertical position. One of the devices of the present invention may be installed in the lower end of either one or both of the side rails of a sash, or could be installed in the upper end of such rail.

One of the spring tension or friction spring members of the present invention is best illustrated in Fig. 4 of the drawings, and is indicated, as a whole, by the reference numeral 20. The friction spring or element 20 is formed of a single piece or strip of strap metal which is shaped as shown while in an annealed condition, and which is thereafter tempered to provide an inherent resiliency tending to keep the strip in its pre-formed shape.

The element 20 consists substantially of a straight flat end portion 21 which may well be termed as the bracket, a slightly bent or off-set portion 22, and a loop portion 23 which forms a complete convolution. The other end portion of the strip, after the loop is made, continues inside the loop beyond the off-set portion 22, and rests

upon inside surface of the lower portion of the loop. This latter end portion is indicated by the reference numeral 24, and is free to move along the inside surface of the loop portion, should the sides thereof be pressed toward each other. Should the sides of the loop 23 be pressed toward each other, their inherent resiliency will resist such bending pressure, and the free end portion 24 will act to further resist such pressure. The resistance supplied by the end portion 24 is considerably greater than that furnished by the loop sides, because when the two sides are moved toward each other, the end portion 24 must eventually deform upwardly. Since the end portion 24 is almost straight, and is short in length, it offers more resistance to deformation than the mere flexing of the two sides of the loop.

That portion of the loop 23 which lies most remote from the free end portion 24 is reduced in width as shown at 25.

In Figs. 2 and 3, the friction member 20 is shown installed in the lower end of a groove 26 which is formed in the outer edge surface of the side rail 4 of the upper window sash 2. The element 20 is installed by merely forcing it upwardly into the groove, and then tacking it in place with a nail 27 inserted through a slot 28 in the bracket portion 21 of the element. The depth of the groove is less than the normal width of the loop 23, and consequently when the element 20 is forced into the groove, its sides are compressed inwardly toward each other. The inherent resilience of the loop therefore causes its two sides to exert an outward pressure against the side member 9 of the window frame, and also against the bottom of the groove.

The lower end of the helical spring 10 is hooked into the upper end of the loop 23, and its upper end is attached to a hook 29 rigidly mounted on the window frame side member 9 adjacent the upper end thereof.

Ordinarily, one of the elements 20 installed at each lower corner of a sash will furnish sufficient friction with the frame member 9 to hold the sash in any vertical position to which it is moved. However, if the sash is exceptionally large or heavy, more friction may be necessary. In order to meet such occasions, an arcuate reinforcing element 30 is provided.

The element 30 (Fig. 4), is also made of spring steel, and when in its normal form, constitutes an open sided loop as shown. When increased friction is desired, one of the elements 30 is compressed and is inserted into the loop 23 of the friction element 20. More than one of the reinforcing elements 30 may be used within the loop 23, if desired.

Of course, the friction elements 20 may be similarly installed in the lower ends of the two side rails 4 of the bottom sash 3.

In cases in which sash weights are used to balance the weight of the window sash, the grooves 26 are not needed. In such cases, a comparatively short cavity 31 is provided in the lower end of each side rail 4 of the sash, and one of the friction elements 20 is inserted therein. Such an installation is shown in Figs. 5 and 6.

Fig. 6 illustrates the manner in which two of the friction elements may be assembled together and installed so that their resilient energy is compounded. Since the slot 28 in each bracket 21 is elongated, the nail 27 may be inserted through both slots and driven into the sash rail. One or more of the reinforcing elements 30 may also be used in this double installation.

From the above description, it is thought to be evident that by compounding the elements 20 and 30, sufficient friction may be obtained to accommodate most window sashes of conventional dimensions and construction.

Obviously the invention is susceptible to some change or alteration without defeating its practicability, and I therefore do not wish to be confined to the preferred embodiment shown in the drawings and described herein, further than I am limited by the scope of the appended claims.

I claim:

1. A spring for producing friction between a window frame and the edge of a vertically slideable window sash, including: a loop of resilient strip metal; means for anchoring the loop to the sash; and a loop-like spring element having both its ends free so that they may be telescoped to reduce the normal size of the element, said

20 spring element adapted to be nested within the first loop to resiliently reinforce the same.

2. A spring for producing friction between a window frame and the edge of a vertically slideable window sash, including: a loop of resilient

25 strip metal adapted to nest in a channel formed in said sash edge, and to slidably contact the adjacent surface of the window frame; means for anchoring said loop in said channel; and a loop-like spring element having both of its ends free

30 so that they may be telescoped to reduce the normal size of the element, said spring element adapted to be nested within the first loop to

resiliently reinforce the same.

3. A spring for producing friction between a window frame and the edge of a vertically slideable window sash to support the sash in the frame, including: a strip of resilient sheet metal

35 bent longitudinally outward upon itself to form a hollow loop with one end of the strip confined within the loop and free to move longitudinally therein to resiliently reinforce the same; an outwardly extending off-set portion formed by the strip and projecting from the loop; and an end portion extending laterally from the off-set portion and forming an anchoring bracket for the strip.

4. A spring for producing sash-supporting friction between a window frame and the edge of a vertically slideable window sash, including: a strip

50 of resilient sheet metal bent longitudinally outward upon itself to form a hollow loop with one end of the strip confined within the loop and free to move longitudinally therein to resiliently reinforce the same, said loop adapted to nest in a channel formed in said sash edge; an outwardly extending off-set portion formed by the strip and projecting from the loop; and an end portion extending laterally from the off-set portion along another edge of the sash and forming an anchoring bracket for holding the loop in said sash channel.

HARRY B. FORESMAN.
